(57) **CLAIM**

The ornamental design for a light as shown and described.

DESCRIPTION

FIG. 1 is a front, right and top perspective view of a light, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is an enlarged view of detail 9 in FIG. 1.

FIG. 10 is a front, right, and top perspective view thereof, shown in an environment of use; and,

FIG. 11 is a front, right, top, and exploded perspective view thereof.

The evenly-spaced broken lines illustrate portions of the article and form no part of the claimed design. Additional broken lines illustrating aquatic life shown in FIG. 10 illustrates environmental subject matter and forms no part of the claimed design. The dot-dash broken lines illustrate boundaries of the enlarged views and form no part of the claimed design.

1 Claim, 11 Drawing Sheets
